UNITED STATES PATENT OFFICE.

HOWARD W. MINNICK, OF MCKEESPORT, PENNSYLVANIA.

ASH-SPRAYING APPARATUS.

Application filed June 24, 1926. Serial No. 118,179.

This invention relates to spraying devices and more in particular to ash-spraying devices to be used in connection with coal or other solid fuel burning furnaces and the like.

The primary object of this invention is to provide a device for spraying ashes while still in the ash-pit of a furnace for the purpose of preventing the formation of dust as well as for facilitating the handling of said ashes. Another object of this invention is to provide a spraying device which is substantially automatic in that the ashes are sprayed at the time that the ash-door of a furnace is opened. A further object is to provide such a spraying device whereby the intensity of the spray may be regulated within desired limits by means of the ash-door of the furnace. Still another object is to provide a spraying device for ashes which is very simple in construction, positive in operation and which may be applied easily to old furnaces as well as be readily incorporated in new ones without great expense in material and labor. Additional features and advantages of this invention may appear in the course of the following description considered in connection with the accompanying drawing forming part of this application and in which:

Fig. 1 is a fragmentary front-elevation, partly shown in vertical section, of a common coal furnace for use in average size residences.

Fig. 2 is a plan view of a section taken substantially on line 2-2 in Fig. 1.

Fig. 3 shows a plan view of a spiral spray-tube used preferably with small furnaces or boilers of the round type.

Fig. 4 represents another design of spray-tube used in connection with small furnaces or boilers of the square or rectangular type, said spray-tube being cast in one piece and made preferably of malleable iron.

Fig. 5 illustrates a spraying apparatus built up of lengths of pipe and standard pipe-fittings and especially intended to be applied to large furnaces or boilers.

Fig. 6 is a side elevation of a special valve used in my invention for controlling the supply of the spray-water from a water-main.

Fig. 7 is a section through a spray-tube, showing the preferred arrangement of the spray-holes therein.

Referring to the drawing, my ash spray-

ing apparatus comprises a spray-tube 1 suitably secured to the base 2 of a furnace 3 a suitable distance below the grate 4 of the latter. This spray-tube is controlled by the lever-valve 5 which in turn is connected to a water-main by means of the pipe 6.

As shown especially in Fig. 6, this valve is composed of a valve body 7 having a vertically movable and spring-closed plunger-stem 8 provided at its upper end with a forked head 9 whereby the stem is connected, by means of the pin-connection 10, to the operating lever 11 which is supported and guided for up and down rocking movement by means of the unitary yoke member 12 secured on the valve body and having two upright arms 13 and 14, the former serving as a fulcrum for the lever and the latter arm having a longitudinal slot 15 to receive therein the lever and guide same.

The inner portion 16 of the lever has a uniform width, but the lower edge of the outer portion 17 tapers downwardly from the end and is provided with three or more steps 18, 19 and 20, and with a stop-lug 21. These steps are intended to be engaged by the top edge 22 of the ash-door 23, the latter being used to operate the valve lever in the following manner:

The valve having been properly installed in relation to the ash-door, when the latter is opened it engages the first step 18, the purpose of which engagement being to merely hold the door in its opened position, to produce a greater draft or enable a person to ascertain the amount of ashes in the ash-pit. When in this position the valve plunger is not affected to cause a spray of water. Upon further opening of the door, the latter will engage the step 19 and cause a moderate flow of water through the spray-tube upon the ashes, and finally, as the ash-door is swung full open, it will engage the step 20 and lift the operating lever 11 still more thereby causing a maximum spray of water on the ashes. Further movement of the door will be arrested by the stop-lug 21.

While the ashes are being sprayed, they may be shoveled out of the pit or, if preferred, the spraying may be continued until all the ashes have been thoroughly wetted, after which the ash-door is brought back into engagement with the first step 19 and the ashes then removed. As will be readily understood, this spraying of the ashes will prevent all formation of dust and at the

same time also greatly compact the ashes so that they may be removed more easily and their bulk greatly reduced.

To facilitate the engagement of the lever by the door, the former is preferably rounded off at its outer and lower end, as indicated in Fig. 6 by the numeral 34.

The spray-tube is, of course, shaped and dimensioned to suit the type of furnace or boiler upon which it is applied. Thus, in Fig. 3 there is shown a spiral spray-tube made of a single piece of pipe suitably bent; this spray-tube is to be applied to small circular furnaces or boilers. As stated before, Fig. 4 represents a cast spray-tube adapted for furnaces of the square or rectangular type. This spray-tube consists of a manifold 24 having a threaded hub 25, for connection to a water supply pipe, and upon which any desired number of branches 26 are cast. These branches are provided with spray-holes 27, generally disposed in staggered relation in two rows, to throw water over a large area.

For larger boilers and furnaces, I prefer, for reasons of economy, to make use of a built-up spray-tube which is made up of a large manifold pipe 28 composed of short lengths of pipe which are connected together by means of the T-fittings 29 to which are also screwed the branch-pipes 30, the outer ends of which are closed in any desired and suitable manner, such as by the pipe-caps 31. The last branch-pipe is preferably secured to the manifold by means of a reducer elbow pipe fitting 32, as shown in Fig. 5. The branch-pipes are, of course, perforated with two or more rows of spray-holes 33.

As will be understood, as suggested herein, there may be slight changes made in the construction and arrangement of the details of my invention without departing from the field and scope of the same, and I intend to

include all such variations, as fall within the scope of the appended claims, in this application in which the preferred forms only of my invention have been disclosed.

I claim:—

1. In combination with a furnace having an ash-door, a water spraying system adapted to spray water over the ashes deposited in the ash-pit of said furnace, said system comprising a spray-tube and a spring-closed valve arranged to control said tube; an operating lever for said valve, said lever having a plurality of graded steps adapted to be engaged by said ash-door to operate said valve, the first of said steps being adapted to hold said door in open position only and the last step being adapted to open said valve to effect the maximum spray of water, and the intermediate steps also being adapted for successive engagement by said door to open said valve gradually.

2. In combination with a furnace having an ash-door, a water spraying system adapted to spray water over the ashes deposited in the ash-pit of said furnace, said system comprising a spray-tube and a spring-closed valve arranged to control said tube; an operating lever for said valve, said lever having a plurality of graded steps adapted to be engaged by said ash-door to operate said valve, the first of said steps being adapted to hold said door in open position only and the last step being adapted to open said valve to effect the maximum spray of water, and the intermediate steps also being adapted for successive engagement by said door to open said valve gradually, and stopping means positioned on said lever and adjacent said last step for limiting the swing of said ash-door.

In testimony whereof I affix my signature.

HOWARD W. MINNICK.
